DESIGN FOR AN ADJUSTABLE LAMP

Otto G. Hildebrand, Cleveland, Ohio, assignor
to Railley Corporation, a corporation of Ohio

Application September 22, 1936, Serial No. 64,961

Term of patent 7 years

To all whom it may concern:

Be it known that I, Otto G. Hildebrand, a citizen of the United States, residing at Cleveland, in the county of Cuyahoga and State of Ohio, have invented a new, original, and ornamental Design for an Adjustable Lamp, of which the following is a specification, reference being had to the accompanying drawing, forming part thereof, wherein Fig. 1 is a view in side elevation of an adjustable lamp embodying the design supported upon a wall; Fig. 2 is a view of the same

lamp with the upper part moved to a different position and showing the lamp as it appears when supported upon a table or the like; Fig. 3 is a top plan view of the lamp as it appears in Fig. 2; and Fig. 4 is a view in front elevation of the lamp as it appears in Fig. 1.

I claim:—

The ornamental design for an adjustable lamp, substantially as shown and described.

OTTO G. HILDEBRAND.
